UNITED STATES PATENT OFFICE.

LOUIS WEINSTEIN, OF NEW YORK, N. Y.

VENDING-MACHINE.

1,191,377.

Specification of Letters Patent. Patented July 18, 1916.

Application filed November 28, 1914. Serial No. 874,433.

To all whom it may concern:

Be it known that I, LOUIS WEINSTEIN, a citizen of the United States, and a resident of New York, borough of Brooklyn, county 5 of Kings, and State of New York, have invented certain new and useful Improvements in Vending-Machines, of which the following is a full, clear, and exact description.

This invention relates more particularly 10 to a small compact vending machine for confections and which is adapted to be placed on the back of seats of places of amusement and especially places of amusement where moving pictures are exhibited.

15 One of the principal objects of the invention is to provide a vending machine in which confections or other articles are positively delivered by means operated by a coin and which means is so constructed and arranged that it is not only simple in construction but is not easily tampered with to secure a confection without the use of a coin.

Another object of the invention is to provide simple and efficient means whereby 25 coin-operated mechanism for the delivery of the confections or articles will be positively locked against movement when the last article has been ejected from the machine.

Other objects are to provide simple and 30 efficient means whereby the mechanism is protected so as to be substantially burglar proof in order that the machine may not be easily robbed; to provide simple means for locking the mechanism against movement 35 except by the deposit of a coin; to provide means which will prevent the use of washers with holes therein; and to provide a machine which is very compact and may be made in box form comparatively small yet 40 having reasonable capacity for a number of articles so that said machine may be placed in the cheapest class of places of amusement where it is desirable to have an article the sale of which usually costs a penny.

45 A further object of the invention is to provide simple and efficient means whereby the casing may be made in parts detachably held together and part of the mechanism supported on one part of the box and another 50 part of the mechanism on another part of the box.

With these and other objects in view, the invention will be hereinafter more particularly described with reference to the accompanying drawings, which form a part of this specification, and will then be pointed

out in the claims at the end of the description.

In the drawings, Figure 1 is a vertical section of one form of machine embodying my 60 invention, taken on the line I—I of Figs. 2 and 5. Fig. 2 is a vertical section taken on the line II—II of Fig. 1. Fig. 3 is a vertical section taken on the line III—III of Fig. 1. Fig. 4 is a rear elevation of the upper part 65 of one member or section of the casing showing the means for locking the coin slide against movement. Fig. 5 is a sectional plan view taken on the line V—V of Fig. 3; and Fig. 6 is a fragmentary view of a part 70 of the hopper for the articles showing how the article ejector may be locked when the articles have all been removed.

The box or casing 10 comprises a front member or section 11 and a back plate, section or member 12. The member 11 has a front 13, a top 14, and sides 15, while the rear section or member 12 has a plate portion 16 and an angular part 17 forming a bottom for the casing. When these two 80 members are brought together, they form a box-like substantially rectangular casing which may be locked and held together in any desired way. As one means of holding the two members or sections detachably together, I provide on the sides 15 of the front member 11, angular brackets 18 at the upper and lower portions thereof having slots at their lower ends which are adapted to be engaged by hook-shaped parts 19 secured to or formed integral with the plate portion 16 of the member 12, so that by a slight sliding movement, the two box sections or casing members are interlocked, there being in addition to this a suitable key-operated locking 90 means to prevent the box sections from being removed or separated from each other except by the person having proper access thereto. The casing member 12 is adapted to be secured to the back of a chair or other support in a position convenient for a person to deposit a coin, and said back is so held that the front part of the casing may be removed when it is desired to fill the machine 95 with articles to be sold or access is to be had to the interior of the casing.

A hopper or chute 20 is arranged upon the rear section 12 and is adapted to hold the articles to be purchased by depositing a coin in the machine. This hopper is vertically arranged in the machine and has a rear wall 21 and angular walls 22 forming an

open space at the front of the hopper to adapt the goods or articles to be readily deposited therein. The bottom of the hopper has lips or parts 23 to provide a slot or space 24 between the same and at the same time support the edges of the articles 25. The articles 25 are superposed and may be of any confection or other article to be sold, and these articles are normally forced downwardly by means of a weight 26. A lever 27 is located at the rear of the hopper 20. This lever is pivoted, at 28, to the casing of the machine and has its lower end provided with a substantially L-shaped part 29, the upper end of which has a lip 30 which is adapted to engage one end of the article to be delivered and to push the same horizontally and laterally so that it will fall upon an inclined platform and into a substantially box-shaped holder 32, there being an opening or channel 33 through which the article passes. The article as it is delivered is adapted to be removed by the purchaser through an opening 34 at the front of the machine casing, the box-like holder 13 serving to prevent access through the opening 34 to the interior of the working parts of the machine or the articles remaining therein. It will be evident that when the lever 27 is moved the proper distance, the lip 30 will travel the entire width of the hopper 20 and will positively force the lowermost article out of the hopper and deliver the same into the box or other holder 32.

To operate the ejecting lever 27 in one direction to restore it to its normal position, I provide a spring 35 one end of which is secured to a part of the machine casing and the other end to a part of the lever above the pivot 28, and to positively operate the lever 27 by a coin, I provide a slide 36. This slide is of a plate-like character and is adapted to move back and forth between the top 14 of the casing member 11 and the top plate 38 of a bracket 39, the latter being secured to the front wall of the casing member 11. The inner end of the slide 36 has a downwardly projecting lip or end 40 which is normally located between two lips or projecting parts 41 of the lever 27 to adapt the lever to be positively moved by the slide in one direction, and when the slide is released permitting the spring 35 to return the lever and slide to their normal position as shown in Fig. 1. This form of connection between the upper end of the lever 27 and the slide serves to permit separation between the said lever and the slide so that the front section or member 11 of the casing may be readily detached from the rear section or casing 12 and at the same time permit the sections to be restored to operative position without the necessity for operating or manipulating any of the mech-

anism. The top 14 of the casing is provided with a slot or opening 42 of substantially the size of a coin to be used in the machine and this slot is adapted normally to register with an opening 43 in the slide 36, the latter being provided with a curved pull or finger portion 44 by which the slide may be manually manipulated.

Suitable means is provided whereby the slide may be locked against movement except when a proper coin is deposited in the machine. This may be accomplished in various ways. As shown, there is provided a substantially U-shaped member or locking element 45. This element may comprise two spaced arms 46 and 47 which are connected by a tie or spacing bar 48. The arms 46 and 47 are pivotally held to a pin or bolt 49 which is held to lugs 50 forming a part of the bracket 39. The arm 47 has a locking end 51 which is adapted to pass through an opening 52 in the bracket 39 and in its normal position engages a slot 53 in one edge of the slide 36 and holds the slide against movement until the locking end is disengaged from said slot, one edge of the slot as well as the upper edge of the end 51 being beveled to permit ready reengagement of the locking end with said slide. At 54 is a finger which is bent upward and at an angle so as to extend through an opening in the top plate of the bracket 39 and into a slot 55, Figs. 1 and 5, in the slide 36. This finger is in the path of movement of the coin and may be located at any desired point so that it is not easily accessible to a tool or other means from the outside. This finger projects upward far enough so that when the coin is moved a certain distance by the movement of the slide after being deposited in the opening 43 to engage and ride over said finger, the arm 47 will be forced downward which will release the locking end 51 of said arm from locking engagement with the slide 36. This will permit the said slide to continue its movement and to force the ejecting lever 27 on its pivot and cause the lip 30 to positively force the lowermost article from the hopper 20 and deposit the same in the holder 32 in position for removal by the purchaser. On the release of the pull or finger piece 44 by which the slide is manipulated, the lever 27 and slide 36 will be restored to their normal position by the spring 35 which will permit the locking end 52 to reengage the slot in the slide 36 and lock the same against movement, the said arm 47 as well as the arm 46 being normally forced upward by means of a flat or other spring 56, one end of which is secured to the bracket 39 and the other end normally resting against the tie bar or connection 48 between said arms 46 and 47. The finger 54 by which the slide is released when the coin engages said finger is of such a character that if a washer with 130

an opening for example is used, the said finger will pass into the opening in said washer and the end 51 of the locking element will lock the slide from complete movement and consequently the article will not be delivered by the lever 27. This is secured by the end 51 entering a slot or notch 56^a in the slide to prevent complete movement of the slide and thereby the delivery of the article, 10 but may have one edge beveled to permit the return of the slide to its coin receiving position.

The coin when the slide is forced inward will be beyond the finger 54 and as there is 15 an opening through the bracket 39, the said coin will pass from the opening 43 in the slide and drop on to a plate 57 and be guided thereby into a coin holder 58. This coin holder is secured to the rear section 12 of the 20 machine casing and is of a box-like form having a sliding bottom 59 and an inclined plate 60 so that when the front of the machine is removed for access to the interior, the bottom 59 may be pulled outward and 25 by holding the hand under the plate 60 the coins deposited into the machine will fall into the hand.

The weight 26 is intended normally to 30 force the articles downward in the hopper 20 and said weight is provided with a slot 35 61. The purpose of this slot is to cause the lever 27 to be automatically locked against movement when all of the articles have been delivered from the hopper 20. When the last article 25 has been delivered, the weight 40 26 will then take the position of the last article so that on the return movement of the lever 27 to its normal position, the lip portion 30 of the angular part 29 of said lever will enter the slot 61 as shown in Fig. 45 6, thus preventing any further backward movement of the slide, so that a purchaser will not be able to deposit a coin and will thereby know that there are no more articles to be purchased.

From the foregoing, it will be evident that a simple and compact vending machine is provided which is adapted to be placed on the back of chairs in amusement places; that 50 said machine may be used for vending various articles; that simple means is provided whereby confections or other articles may be positively delivered from the machine; that effective means is provided whereby the machine cannot be easily tampered with; that 55 simple means is provided whereby one part of the machine casing may be made separable from the other for access to the interior thereof; that simple means is provided for locking the coin-operated mechanism against 60 movement when the last article is sold; and that simple means is provided whereby a

coin of only a certain size and kind may be employed in the machine.

Having thus described my invention, I 65 claim as new and desire to secure by Letters Patent:—

1. In a vending machine, the combination of a casing, a hopper located in said casing and adapted to hold articles in superposed relation, a lever extending lengthwise of the hopper and having an angular end provided with a lip adapted to move entirely across the hopper to positively force an article therefrom, means for receiving the articles 75 when delivered from the hopper, a spring normally forcing the lever in one direction, a slide having an angular end adapted loosely to engage a part of the ejecting lever, means for moving the slide in one direction, said slide having an opening for the reception of a coin, a locking element having one part adapted to lock the slide against movement and another part arranged in the path of the coin and adapted to be actuated 80 thereby during the movement of the slide to release the slide from locking engagement with said element, and a spring normally forcing said element in position to again lock the slide when in its normal position. 90

2. In a vending machine, the combination of a casing, comprising two separable members, coin controlled mechanism, a part of which is mounted on each member comprising a hopper adapted to hold articles in superposed relation, a lever extending lengthwise of the hopper and having an angular lower end provided with a lip adapted to move entirely across the hopper to positively force an article therefrom, the upper end of 95 the lever having lips or projections extending toward the front of the casing, means for receiving the articles when delivered from the hopper, a spring normally forcing the lever in one direction, a slide having an 100 angular end adapted loosely to engage the lever between said lips or projections, means for moving the slide in one direction, said slide having an opening for the reception of a coin, a locking element having one part 105 adapted to lock the slide against movement and another part arranged in the path of the coin and adapted to be actuated thereby during the movement of the slide to release the slide from locking engagement with said 110 element, and a spring normally forcing said element in position to again lock the slide when in its normal position. 115

This specification signed and witnessed this 25th day of November, A. D. 1914.

LOUIS WEINSTEIN.
